UNITED STATES PATENT OFFICE

HARRY B. CRUMBAUGH, OF GREENVILLE, TEXAS

AEROPLANE

Application filed February 26, 1929. Serial No. 342,923.

The present invention relates generally to aeroplanes and more particularly to a landing gear and launching apparatus associated therewith.

5 The prime object of the invention resides in the provision of means whereby the aeroplane may be raised suddenly and quickly from the ground in the take off.

10 Another very important object of the invention resides in the provision of an apparatus for throwing the aeroplane in the air at the take off controlled by compressed air stored in a tank in the aeroplane.

15 Another very important object of the invention resides in the provision of a tail wheel for the aeroplane with an air brake associated therewith.

20 A still further very important object of the invention resides in the provision of an apparatus of this nature which is simple in its construction, easy to manipulate, thoroughly efficient and reliable in use and operation, and otherwise well adapted to the purpose for which it is designed.

25 With the above and numerous other objects in view as will appear as the description proceeds, the invention resides in certain novel features of construction, and in the combination and arrangement of parts as will be hereinafter more fully described and claimed.

In the drawing:

Figure 1 is a front elevation of an aeroplane embodying the features of my invention,

30 Figure 2 is a sectional fragmentary side elevation thereof,

Figure 3 is a side elevation partly in section of one of the supporting wheels.

35 Figure 4 is an enlarged detail section through the control valve.

Figure 5 is an enlarged detail vertical section taken substantially on the line 5—5 of Figure 1.

40 Figure 6 is a diametric detailed section taken substantially on line 6—6 of Figure 5, and looking in the direction of the arrows, and

45 Figure 7 is an enlarged detailed section through the tail, showing particularly the brake associated with the tail wheels.

Referring to the drawing in detail, it will be seen that the numeral 5 denotes an aeroplane fuselage of any preferred construction which has depending from the forward portion thereof a frame structure 6 to which is pivotally engaged a truck comprising a frame F which includes side arms 7 pivotally engaged as at 8 with the frame 6 and a cross bar 9 braced in respect to the arm 7 as at 10. Wheels 11 are journaled on the extremities of the brace members 10 at the lower ends of the arms 7, said brace members terminating in axles 12 for this purpose.

The wheels 11 are provided with hubs 14 having a plurality of recesses 15 therein tapering in like directions so that balls or the like 16 mounted in the recess will wedge against the axle when the wheels are rotated in a reverse direction that is the wheels are free to rotate in the direction of the arrows 17 in Figure 3 but are prevented from rotating in opposite directions.

An arcuate cylinder 18 is mounted on the fuselage as at 19 in any preferred manner so as to be concentric in respect to the pivots 8 and this cylinder is braced in respect to the frame 6 by suitable brace structure 20. A piston 21 is slidable in the cylinder and has a curved rod 22 extending therefrom and slidable through the head 23 at the bottom 29 end of the cylinder and said rod is fixed as at 24 to the cross bar 9.

Buffer springs 26 and 27 are located in the ends of the cylinder. A head 28 at the upper end of the cylinder is coupled with a pipe 29 leading from a valve V. A pipe 30 leads from the bottom of the cylinder 18 to the valve V.

A buffer spring 31 is disposed about the rod 22 to the outside of the cylinder 18. A support 33 depending from the tail or rear end of the fuselage has rotatably mounted thereon a tail wheel 34 with a brake drum 35 attached thereto. A brake band 36 is disposed circumjacent the drum 35 and controlled by a lever 37 pivotally mounted as at 38 on the support 33.

A cylinder 39 operates the lever and has an air pipe 40 leading thereto from the valve V. The valve V comprises a casing 42 into

which extends pipes 29, 30 and 40. The pipes 30 and 40 are located at 180 degrees from each other and the pipe 29 is located 90 degrees from the pipes 30 and 40. 180 degrees from the pipe 29 is an exhaust opening 43 in the casing.

5 A core 44 is rotatable in the casing receiving air through opening 45 from a pipe 46 leading from an air tank 47. An opening 48 10 is provided in the core so as to be registerable with pipes 29, 30 and 40. An exterior channel 49 is provided in the core for permitting escape of air.

15 With the parts disposed as shown in Figure 4 it will be seen that with the valve V in the position shown in Figure 5, compressed air passes through the pipe 29 to force the piston 21 downwardly and swing the truck frame F rearwardly and since the wheels 11 are prevented from rotating in reverse direction the aeroplane is lifted forwardly and upwardly so as to obtain a quick efficient take off.

20 The air forced from the cylinder escapes through pipe 30, channel 49 and opening 43. 25 The truck frame F is returned to its raised position by turning the core 44 so as to register the opening 48 with the pipe 30.

25 When landing the brake may be applied on the wheel 34, bringing the opening 48 in registry with the pipe 40, as will be quite apparent and thus landing may be made in a relatively small distance. In landing the shock on the running gear is taken care of by frames 27 and 31 as will be quite apparent.

35 It is thought that the construction, utility and advantages of this invention will now be quite apparent to those skilled in this art without a more detailed description thereof. The present embodiment of the invention has 40 been disclosed in considerable detail merely for the purposes of exemplification since in actual practice it attains the features of advantage enumerated as desirable in the statement of the invention and the above description.

45 It will be apparent that changes in the details of construction, and in the combination and arrangement of parts may be resorted to without departing from the spirit 50 or scope of the invention as hereinafter claimed or sacrificing any of its advantages.

Having thus described my invention, what I claim as new is:

1. In an aeroplane of the class described, 55 a wheeled frame, means for rockably mounting the wheeled frame on the aeroplane, and means for swinging the frame to kick the aeroplane off the ground, said means comprising an arcuate cylinder concentric with the 60 axis of the rockable frame, a piston slideable in the cylinder, a rod extending from the piston and attached to the frame and compressed air means associated with the cylinder to operate the piston.

65 2. In an aeroplane of the class described,

a wheeled frame, means for rockably mounting the wheeled frame on the aeroplane, and means for swinging the frame to kick the aeroplane off the ground, said means comprising an arcuate cylinder concentric with the axis of the rockable frame, a piston slideable in the cylinder, a rod extending from the piston and attached to the frame and compressed air means associated with the cylinder to operate the piston, buffer springs located in the ends of the cylinder, a buffer spring on the rod exteriorly of the cylinder. 70 75

3. In an aeroplane of the class described, a wheeled frame, means for rockably mounting the wheeled frame on the aeroplane, and means for swinging the frame to kick the aeroplane off the ground, said means comprising an arcuate cylinder concentric with the axis of the rockable frame, a piston slideable in the cylinder, a rod extending from the piston and attached to the frame and compressed air means associated with the cylinder to operate the piston, buffer springs located in the ends of the cylinder, a buffer spring on the rod exteriorly of the cylinder. 80 85

4. In an aeroplane of the class described, 90 a wheeled frame, means for rockably mounting the wheeled frame on the aeroplane, and means for swinging the frame to kick the aeroplane off the ground, said means comprising an arcuate cylinder concentric with the axis of the rockable frame, a piston slideable in the cylinder, a rod extending from the piston and attached to the frame and compressed air means associated with the cylinder to operate the piston, the wheels of the frame having incorporated therein means allowing them to freely rotate forwardly and preventing them from rotating rearwardly. 95 100

5. An aeroplane of the class described including a fuselage, a wheeled frame, means 110 for rockably mounting the wheeled frame on an aeroplane, and means for swinging the frame to kick the aeroplane off of the ground, said means comprising an arcuate cylinder concentric with the axis of the rockable frame, a cylinder slideable in the piston, a rod extending from the piston and attached to the frame for compressed air means associated with the cylinder to operate the piston, the wheels of the frame having incorporated therein a means allowing them to freely rotate forwardly and preventing them from rotating rearwardly, a depending structure at the tail of the fuselage, a wheel journaled on said structure, a brake associated with said 115 wheels, and means for operating said brake. 120 125

In testimony whereof I affix my signature.

HARRY B. CRUMBAUGH.
